(57) **CLAIM**

The ornamental design for an input selection mechanism, as shown and described.

DESCRIPTION

FIG. 1 is a front, right and bottom perspective view of the input selection mechanism, showing a networked device in broken lines;

FIG. 2 shows a bottom plan view of the input selection device, showing a networked device in broken lines;

FIG. 3 shows a right side elevational view of the input selection device, showing a networked device in broken lines;

FIG. 4 shows a top plan view of the input selection mechanism, showing a networked device in broken lines with no part of the input selection visible;

FIG. 5 shows a left side elevational view of the input selection mechanism, showing a networked device in broken lines with no part of the input selection visible;

FIG. 6 shows a front plan view of the input selection mechanism, showing a networked device in broken lines; and,

FIG. 7 shows a rear elevational view of the input selection mechanism, showing a networked device in broken lines.

The broken lines showing parts of the case, power socket and power plug, are for illustrative purposes only, and form no part of the claimed design. The dash-dot lines are included to represent the boundaries of the claimed design and form no part of the claimed design.
